UNITED STATES PATENT OFFICE.

JOHN GEORGE HUFNAGEL, OF SCRANTON, PENNSYLVANIA.

NOISELESS STEAM WATER-HEATER.

No. 822,127.

Specification of Letters Patent.

Patented May 29, 1906.

Application filed December 8, 1905. Serial No. 290,943.

To all whom it may concern:

Be it known that I, JOHN GEORGE HUFNAGEL, a citizen of the United States, residing at Scranton, in the county of Lackawanna and State of Pennsylvania, have invented 5 certain new and useful Improvements in Noiseless Steam Water-Heaters; and I do hereby declare the following to be a full, clear, and exact description of the invention, such 10 as will enable others skilled in the art to which it appertains to make and use the same.

This invention relates to improvements in mufflers, and particularly to steam water- 15 heaters.

The object of the invention is the provision of means for facilitating the muffling or discharging of steam from an outlet which may be positioned within a tank or receptacle containing a liquid.

With this and other objects in view the invention consists of certain other novel constructions, combinations, and arrangements of parts, as will be hereinafter fully described, 25 illustrated in the accompanying drawings, and more particularly pointed out in the claims hereto appended.

In the drawings, Figure 1 is a view in side elevation of a device constructed in accordance with the present invention. Fig. 2 is a vertical longitudinal sectional view of the device depicted in Fig. 1, and Fig. 3 is a transverse sectional view of the same.

Referring to the drawings by numerals, 1 35 designates a cylindrical primary casing which is provided with transverse apertures 2. At each end of the casing there is formed an annular integral extension 3.

An auxiliary cylinder 4 is positioned upon 40 the parallel cylinder 1 between the annular extensions or ends 3-3. This cylinder 4 is formed of a wire mesh or screen. Between the primary and auxiliary cylinders 1 and 4, respectively, a compartment 5 is formed. 45 Within this compartment there is positioned porous or fibrous filling means—as, for instance, hemp—which insures of the noiseless discharge of the steam from the apertures 2 of the primary cylinder 1. The auxiliary 50 wire-mesh or screen cylinder 4 is positioned between and lies flush with the outer surface

of the annular extensions or ends 3-3 of the primary cylinder.

Integral with one of the ends 3 is a threaded tubular portion 6. The conducting means 55 for the steam—as, for instance, a hose or pipe—is connected to the muffler by means of this tubular portion 6. It is to be noted that the bore of the tubular portion 6 is of the same diameter as the bore of the primary 60 aperture cylinder 1. By reason of this the steam is not retarded in its passage into the muffler. The passage of the steam from the interior of the primary cylinder to the outer atmosphere is retarded by two means—to wit, 65 a cylindrical hemp jacket and a wire-mesh cylinder. Although I preferably use hemp for forming the cylindrical filling-jacket, in some instances other fibrous filling means may be employed.

70 My improved muffler is particularly adapted to be secured to the discharge end of a hose or tubing which is positioned within a tank or receptacle containing liquid which is to be heated. The discharge of the steam through 75 the three cylinders or casings constituting my muffler is comparatively noiseless.

What I claim is—

1. A device of the character described, comprising a primary cylinder, formed with 80 rows of staggered radiating apertures therein, enlarged ends formed integral with said cylinder, an auxiliary wire-mesh cylinder secured to said primary cylinder and lying flush with the outer surface thereof, and a 85 cylinder of fibrous material interposed between said primary and auxiliary cylinders.

2. A device of the character described, comprising a cylinder, formed with staggered apertures therein, closed at one end, a tubular threaded portion upon its opposite end, a wire-mesh cylinder positioned between the ends of said primary cylinder, and a hemp filling positioned between said primary and auxiliary cylinder.

95 In testimony whereof I affix my signature in presence of two witnesses.

JOHN GEORGE HUFNAGEL.
